UNITED STATES PATENT OFFICE.

WILLIAM JUSABRO IWAMI, OF NEW YORK, N. Y.

TYPEWRITER ATTACHMENT.

1,426,195.

Specification of Letters Patent. Patented Aug. 15, 1922.

Application filed June 18, 1921. Serial No. 477,141.

To all whom it may concern:

Be it known that I, WILLIAM J. IWAMI, a subject of the Emperor of Japan, and resident of the city of New York, borough of 5 Manhattan, in the county of New York and State of New York, have invented a new and Improved Typewriter Attachment, of which the following is a full, clear, and exact description.

10 My invention relates to a typewriter attachment, and aims to provide a device of this nature by means of which the type may be cleaned.

It is a well appreciated fact that heretofore it has been necessary to clean the faces of the type in a writing machine at frequent intervals, incident to the fact that the type becomes clogged with particles of ribbon, dust, etc. rendering the impression made 20 by the type blurred. This cleaning operation necessitates the use of a brush or a sharp pointed instrument, together with a suitable cleaning fluid to effect a dislodgment of the particles.

25 Aside from the time necessary for the accomplishment of the type cleansing, considerable difficulty has been experienced in that the operator's fingers become soiled, incident to the ink from the ribbon rendering the operation an extremely unpleasant one.

Having these defects in mind, my present invention aims to provide a typewriter attachment by means of which the type may 35 be thoroughly and quickly cleaned without the necessity of soiling the fingers.

A further object of my invention is the construction of a device of the nature specified which may be placed upon the 40 market at a nominal figure, and further objects of my invention will appear in the annexed specification taken in connection with the drawings which latter present practical applications of the same, and in 45 which;

Figure 1 is a side view of an attachment embodying my improved construction and showing the same in one association.

Figure 2 is an enlarged end view thereof.

50 Figure 3 is a rear view of a slightly different form of attachment than that illustrated in the preceding figures.

Figure 4 is an enlarged transverse sectional view taken along the line 4-4 and 55 in the direction of the arrows indicated in Figure 3.

Figure 5 is a plan view of still another adaptation of the attachment, and

Figure 6 is a perspective view of the device as illustrated in Figure 5.

60

Referring now more particularly to Figures 2 and 4, it will be seen that the essence of my invention consists in the utilization of a brush element against which the type to be cleaned is struck. Thus, the reference numeral 10 indicates a base upon which a backing 11 carrying bristles 12 is removably retained, preferably by means of a clamping ring 13, thus rendering the brush portion of the device renewable when the same becomes 70 worn.

As in Figures 1 and 2 the base 10 has secured to it a rearwardly extending clip 14 by means of which it may be detachably associated with the type head 15 secured to any 75 type bar 16, forming a part of the conventional typewriter action.

Thus when an operator desires to effect a cleaning of the type it will only be necessary to project one of the type bars by striking 80 one of the keys 17, subsequent to which the brush element may be associated with the head 15 by means of the clip 14. By retaining the depressed key in this position the other keys may now be struck, and by virtue 85 of the fact that the type head 15 with which the cleaning element is associated occupies a central position, each of the type subsequently projected by pressing the corresponding keys will strike against the bristles 90 12 thus freeing the particles of matter lodged within the face of the type and cleaning the latter.

It will be found that all of the type may 95 thus be readily cleansed with the expenditure of but a minimum amount of time and it will also be seen that the fingers of the operator will not be soiled as has heretofore resulted from the accomplishment of this cleaning operation, it being of course understood that after the same is completed, that the base 10 is detached from that type head 100 with which it has been associated, and the key of the latter released.

In Figures 3 and 4 I have shown the cleaning element as forming a permanent part of a typewriting machine, i. e. one of the type bars devoted exclusively as a permanent mounting for the cleaning element thus rendering the attachment and detachment of 110 the latter unnecessary.

Finally in the type illustrated in Figures

5 and 6 it will be seen that the cleaning element aforescribed is attached to the outer end of one of a series of links 18 hingedly interconnected these links when in folded position lying as has been indicated in dotted lines in Figure 5 flush against the body of the typewriting machine, but being capable of being swung so that the cleaning element will lie in advance of the type gap so that 10 obviously any type projected will strike against the same and be cleansed.

Thus all of the objects set forth in the preamble of this specification have been accomplished and it will be appreciated that 15 numerous modifications of structure might readily be resorted to without in the least

departing from the spirit of my invention, which I claim as:

1. A typewriter attachment including in combination with the type bar of a conventional typewriting machine, of a cleaning element detachably secured to said bar. 20
2. A typewriter attachment including a cleaning element and supporting means for said cleaning element, said supporting means being adapted to be associated with a typewriter whereby said cleaning element may be moved to a point adjacent the type guide of said typewriter to permit of the type co-acting therewith. 25

WILLIAM JUSABRO IWAMI.
